UNITED STATES PATENT OFFICE.

JOSEPH RUTKUS, OF MILWAUKEE, WISCONSIN.

TRACTION ATTACHMENT FOR AUTOMOBILES.

1,316,063.

Specification of Letters Patent. Patented Sept. 16, 1919.

Application filed April 21, 1919. Serial No. 291,774.

To all whom it may concern:

Be it known that I, JOSEPH RUTKUS, a citizen of the United States, and resident of Milwaukee, in the county of Milwaukee and State of Wisconsin, have invented certain new and useful Improvements in Traction Attachments for Automobiles; and I do hereby declare that the following is a full, clear, and exact description thereof.

10 My invention relates to new and useful improvements in pulling attachments for vehicles in which a windlass or winch is mounted in operative relation to the vehicle motor and arranged to be driven by the fly-

15 wheel thereof to wind up a cable attached to a fixed object for moving the vehicle out of a mud hole or the like, up a steep incline, or over a slippery surface affording practically no traction.

20 It is the primary object of this invention to provide a simply constructed attachment which, when not in use, will be entirely disconnected from the vehicle motor, but which can be quickly thrown into operation 25 by the engagement of a certain part with the motor fly-wheel.

Another object is to provide an attachment of this character which will be simple and inexpensive in construction and efficient and reliable in operation.

With these and other objects and advantages in view, the invention resides in the novel details of construction and combination of parts more fully hereinafter disclosed and particularly pointed out in the claims.

40 In the accompanying drawings, Figure 1 represents a semi-diagrammatic view of a portion of a motor vehicle having my attachment associated therewith, parts of the latter being in vertical section, as indicated by the line 1—1 of Fig. 2.

Fig. 2 is a plan view, partly in section, of the structure shown in Fig. 1, and

45 Fig. 3 is a detail transverse sectional view taken on the plane of the line 3—3 of Fig. 2.

By reference to the accompanying drawings, it will be seen that the invention is located directly in the rear of the vehicle motor M when the fly-wheel F thereof is at the rear, the structure comprising the invention being hung from suitable brackets carried by

the side bars B of the chassis frame. Since the invention is adapted to be actuated by the motor fly-wheel, its location will be dependent upon the position of the latter, and consequently various minor changes which may be made in the form and proportion of the various parts of the device are also more or less dependent thereon.

In the embodiment illustrated, the invention includes a transverse shaft 1 journaled in bearings 2 carried by brackets 3 which depend below the side bars B and are secured thereto as at 4. Loosely disposed on the shaft 1 is a sleeve 5 in the intermediate portion of which is formed a winding drum 6, a pulling cable 7 being adapted to be wound thereon. One end of the sleeve 5 is provided with clutch elements 8 for co-operative engagement with the elements of a slideable clutch member 9 splined on said shaft 1. A shifting lever 10 provides means for moving the clutch member 9 into and out of engagement with the end of the sleeve 5.

The shaft 1 is operated directly by a worm gear 11 fixed thereto, which in turn is driven by a worm 12 on the lower end of a vertical shaft 13. This shaft 13 is journaled in the vertically spaced bearings 14 and 14¹ of a bracket 15, which, like the brackets 3 is secured to one of the frame bars B. A second worm gear 16 is fixed to the shaft 13 intermediate its ends and is positioned between the spaced bearings 14 and 14¹ as indicated in Fig. 1.

The bracket 15 also includes a pair of spaced pintle bearings 17 in which the pintles 18 that project from opposite sides of a bearing sleeve 19 are journaled. It will be noticed that the pintles 18 are positioned vertically so that the sleeve 19 may be swung in a horizontal plane.

A drive shaft 20 is journaled in the bearing sleeve 19 and is held against longitudinal movement therein by a worm 21 engaged with one end of the latter and a stop collar 22 in contact with the other end. The worm 21 is fixed at one end of the shaft 20 and the opposite end carries a friction pulley 23 which is designed to be intermittently engaged with the periphery of the fly-wheel F. During the engagement of the pulley 23 and the fly-wheel, the worm 21 is

meshed with the teeth of the worm gear 16 so that rotation of said fly-wheel will be transmitted to the shaft 1.

The structure illustrated in Fig. 3, clearly 5 depicts the preferred means for moving the shaft 20 and its bearing sleeve 19 to engage or disengage the fly-wheel F and friction pulley 23. A bracket 24 secured to one of the frame bars B supports the shaft shifting 10 mechanism which includes a collar 25 having oppositely extending pins 26 slidable in ears 27 on the bracket, and a shifting lever 28 which is loosely engaged with the operating finger 29 on the collar.

15 Normally both of the levers 10 and 28 are retained in position to disengage the clutch member 10 from the sleeve 8 and the friction pulley 23 from the fly-wheel F. When, however, the automobile or other motor vehicle equipped with my invention becomes 20 unable to proceed by its own tractive means, the hook 30 on the free end of the cable 7 is attached to a stationary object at a point distant from the vehicle so that upon rotation of the winding drum 6 the cable will 25 be shortened and the vehicle moved forwardly, or backwardly as in some instances. Rotation of the drum is procured in the manner as herein set forth by shifting the collar 25 to rock the drive shaft 20 and engage the worm 21 and the friction pulley 23 with the worm gear 16 and fly-wheel F respectively; and thereafter clutching the sleeve 5 to the shaft 1. The vehicle having 30 been moved to firm ground, or into such 35 position that its drive wheels will function,

the levers 10 and 28 are shifted to inoperative position, and the cable 7 is arranged so as not to interfere with the running of the machine.

I claim:

1. In a machine of the class described, the combination with an engine including a fly wheel, of a winding drum, a driving gear connected with the drum, a bracket, a 45 sleeve pivoted in said bracket, a shaft journaled in said sleeve, means on one end of said shaft for engagement with said driving gear, means on the opposite end of the shaft on the opposite side of said sleeve 50 from the last mentioned means for engagement with said fly wheel, and means for rocking the sleeve to simultaneously engage or disengage the first mentioned means with or from the driving gear and the last mentioned means with or from said fly wheel.

2. In a combination of the class described, the combination with an engine including a fly-wheel, of a winding drum, a worm gear connected with said drum, a bracket having a bearing, a sleeve pivoted in said bearing of the bracket, a shaft journaled in said sleeve, a worm on one end of said shaft for engagement with the worm gear, a friction pulley on the opposite end of the shaft for 60 engagement with the fly-wheel, and means for rocking the sleeve.

In testimony that I claim the foregoing I have hereunto set my hand at Milwaukee, in the county of Milwaukee and State of 70 Wisconsin.

JOSEPH RUTKUS.
